Howard P. Wilson

ATTORNEY

UNITED STATES PATENT OFFICE.

ALONZO, WOODRUFF, OF AUBURN, NEW YORK.

COMBINATION OF BOTTLE CAP AND BRUSH HOLDER.

Application filed July 19, 1921. Serial No. 485,838.

To all whom it may concern:

Be it known that I, ALONZO WOODRUFF, of Auburn, in the county of Cayuga, in the State of New York, have invented new and useful Improvements in the Combination of Bottle Caps and Brush Holders, of which the following, taken in connection with the accompanying drawings, is a full, clear, and exact description.

10 This invention relates to certain improvements in the combination of bottle-cap and brush-holder in which the main body of the cap is preferably made of comparatively inexpensive sheet metal such as tin having a 15 thread rolled thereon for inter-engagement with corresponding thread on the neck of the bottle whereby the cap may be removably secured thereto.

These bottles are adapted to be used as 20 containers for rubber stamp ink and other fluids or semifluids which are to be spread over and upon a surface by means of a brush, and the main object of my invention is to provide a comparatively inexpensive cap for 25 bottles of this character in which all portions of the cap are flush with or within the marginal edge so that the cap may be supported bottom side up with its marginal edge resting flatwise upon any flat surface to cause 30 any fluid or semi-fluid material which may lodge in the cap to rest upon the under side of the top when the cap is resting in an inverted position upon any suitable support and thereby to avoid the spilling of the material 35 on to said support and also enabling the material which may lodge in the cap to readily flow back into the bottle instead of along the sides of the cap when the latter is replaced upon the bottle.

40 Another object is to provide a brush with a hollow longitudinally split shank or handle for expanding and contracting circumferentially so that it may be slipped over and upon the inwardly projecting post of the cap with a friction fit capable of holding the brush in operative position upon said post when the cap is screwed upon the bottle.

Another object is to provide the outer end 45 of the post with a central lengthwise socket for the reception of a removable handle by which the cap with the brush may be manipulated without touching the cap.

Other objects and uses relating to specific parts of the device will be brought out in the 55 following description:

In the drawings:

Fig. 1 is a top plan of a bottle and cap therefor embodying the various features of my invention.

Fig. 2 is a central vertical sectional view of 60 the same bottle and cap showing the brush and handle in operative position.

Fig. 3 is a transverse sectional view of the longitudinally split shank of the brush showing the overlapping edges to enable it 65 to be expanded and contracted circumferentially.

In order that my invention may be clearly understood, I have shown a bottle —1— adapted to contain a rubber stamp ink or 70 other material, said bottle having an externally threaded neck —2— adapted to be engaged with a threaded sheet metal cap —3— for closing and opening the mouth of the bottle.

The cap is preferably made in the form of an inverted cup having a substantially flat top portion —4— and a pendent marginal flange —5— terminating at its lower end with a laterally projecting flange —6— a 80 sufficient distance from the top portion —4— to engage an annular shoulder —7— on the bottle when the cap is tightly screwed in place upon the bottle, said cap being provided with a packing washer —8— of rubber 85 or equivalent material substantially coextensive with and against the underside of the flat top portion —4— to engage the upper end of the mouth of the bottle and thereby to assist in preventing leakage of the contents 90 of the bottle therefrom when the cap is in place.

A brush supporting post —9— extends through a central opening —10— in the top portion —4— and packing washer —8— and is riveted by inner and outer shoulders —11— and —12— against the inner face of the packing washer —8— and outer face of the top portion —4— to firmly hold the post in place on the cap and coaxial therewith, the remaining portion of the post extending toward the open or inner end of the cap and has its inner end tapered at —13— to permit the shank of the brush to be more easily placed in operative position thereon.

105 The brush comprises a sheet metal tubular shank or handle —14— split longitudinally at —15— through one side to permit it to be expanded and contracted circumferentially 110 for sliding frictional engagement with the

inner end of the post —9— to hold the brush in operative position thereon, the inner end of said brush being flattened to retain the bristles as —16—.

- 5 The outer end of the post —9— is provided with a central lengthwise socket —17— for receiving the reduced end —18— of a supplemental handle —19— which may be made of wood or any cheap material capable of supporting and manipulating the cap with the brush thereon when applying the ink or other material to the surface of the pad or other device, it being understood that the stem —18— of a supplemental handle —19— is frictionally fitted in a socket —17— and may be easily withdrawn when desired, as for example, when it is necessary to support the cap bottom side up upon a suitable supporting surface in which case, 10 the marginal edge of the cap will rest upon said surface and cause any ink or other material which may lodge within the cap to col-

lect upon the inner side of the top, thereby obviating any liability of over-flow of that material on to the support and permitting it 25 to readily flow back into the bottle when the cap —3— is replaced upon the mouth of the bottle.

What I claim is:

A bottle cap having a substantially flat 30 top and a downwardly projecting marginal flange threaded for screw engagement with the mouth of a bottle, in combination with a brush holder having a tubular upper end secured co-axially in an opening in said top 35 wholly below the upper flat face thereof, and a handle having a stem slidably engaged in the tubular upper end of the brush holder.

In witness whereof I have hereunto set my hand this 14th day of July, 1921.

ALONZO WOODRUFF.
